140,290

DESIGN FOR A CIGARETTE BOX

Richard Newman, New York, N. Y.

Application September 18, 1944, Serial No. 115,354

Term of patent 7 years

(Cl. D85—2)

To all whom it may concern:

Be it known that I, Richard Newman, a citizen of the United States residing at New York, in the county of New York and State of New York, have invented a new, original, and ornamental Design for a Cigarette Box, of which the following is a specification, reference being had to the accompanying drawing, forming a part thereof.

In the drawing:

Fig. 1 is a perspective view of a cigarette box showing my new design.

Fig. 2 is a side elevational view of the same.

Fig. 3 is a perspective rear view of the same showing the cover in open condition.

I claim:

The ornamental design for a cigarette box, as shown.

RICHARD NEWMAN.
